Attorney.

UNITED STATES PATENT OFFICE.

HAROLD A. BRAMAN, OF PROVIDENCE, RHODE ISLAND.

FIRE EXTINGUISHER.

Application filed March 24, 1922, Serial No. 546,328. Renewed January 2, 1924.

To all whom it may concern:

Be it known that HAROLD A. BRAMAN, a citizen of the United States of America, residing at Providence, in the county of Providence and State of Rhode Island, has invented certain new and useful Improvements in Fire Extinguishers, of which the following is a specification.

My invention relates to fire extinguishers and particularly to an automatic, thermally controlled extinguisher in which is contained two or more different chemicals which when mixed will give off a fire extinguishing gas.

15 The principal object of my invention is to prevent the escape of the chemicals before complete reaction has taken place.

Other and further objects and advantages of the invention will be in part described and in part apparent as the specification is proceeded with.

In the accompanying drawings forming a part of this specification:

Figure 1 is a vertical sectional view through a preferred embodiment of my invention; and

Figure 2 is a vertical sectional view through a modified form of my invention.

Referring more particularly to the drawings the numeral 1 designates a metallic container of any suitable shape. A second metallic container 2 fits within the upper open end of the outer or main container 1 and projects slightly therefrom. The upper ends of both containers are screw threaded externally as at 3 and 4 respectively to receive the rings 5 and 6. A cover plate 7 rests upon and closes the upper end of the inner container while the ring 6 rests upon the upper end of the outer or main container 1 and serves as a support for the inner container 2. It will also be noted that the ring 6 together with the inner container serves as a closure for the outer container 1.

45 When the parts just described are assembled the rings 5 and 6 will be flush with the upper end of the container to which it is attached. Bolts (not shown) passing through aligned openings 9 in the rings and cover plate clamp the parts together and effect air and liquid tight joints.

50 The containers 1 and 2 are filled with any known chemicals which when mixed form an efficient fire extinguishing gas under pressure. It will be noted that the inner

container is about half the height of the outer container and that in consequence when assembled they will each hold about equal amount of chemicals.

The bottom wall 10 of the inner container 1 is formed with valve opening 11, adapted to receive valve guide pins 12 mounted upon and projecting upwardly from the valve 13 which will presently be described in greater detail.

60 The container 1 is provided with an outlet opening 14 in the bottom wall 15 thereof normally closed by a valve 16, having a lead insert 17 in its upper face adapted to be engaged by the tapered ridge 18 formed on the 65 outer face of the bottom wall thus effecting a tight joint.

The valve 16 is maintained in closed position by means of a yoke clamp or rod 19 supported at one end on lugs 20 depending 70 from the container 1. The opposite end of this rod or yoke is connected to the container 1 as at 21 by means of a readily fusible link 22, thereby holding the closure or valve 16 75 tightly to its seat. An adjusting screw 23 permits of the adjustment of the valve after the fusible link has been placed over the bracket 21 and the clamp 19.

80 A tubular nozzle 24 normally seats in the outlet opening 14, the lower end of the 85 nozzle being supported on the valve 16 flush with the outer face of the bottom wall 15 of the container 1. This nozzle is exteriorly threaded at its upper end to receive the interiorly threaded lower end of tube 34 90 the upper end of which is interiorly threaded to receive the enlarged lower exteriorly threaded portion of a guide pin 25, the latter projecting upwardly into the central longitudinal opening 26 in the valve 13. A coil 95 spring 27 bearing at its upper end against the valve 13 and at its lower end against the tube 34 serves to resiliently hold the valve 13 in closed position. This valve 13, like the valve 16 is formed with a lead insert 28 100 adapted to contact with the sharpened ridge 29 formed on the bottom wall of the inner container 2 thereby effecting a gas and liquid tight joint.

105 In the event of fire occurring in proximity to the container 1, the readily fusible link 22 will give way under action of the heat and the spring pressure of the nozzle 24, and the clamp yoke or rod 19 will drop from its seat on the lugs 20. Simultaneously with 110

this movement the nozzle 24 drops down through the outlet opening 14, until it is arrested by the lower end of the tube 34 coming in contact with the bottom wall 15 of the container 1, it being understood that the opening 14 is not sufficiently large to permit of the tube 34 entering therein. As the tube 34 and nozzle move away from the container 2 and valve 13, the tension of coil spring 27 is relieved and the valve 13 opens by gravity. The liquid in container 2 now drops down through opening 11 in container 1.

Heretofore considerable difficulty has been experienced with this general type of extinguisher due to the fact that the liquid would escape from the main container before complete chemical reaction had taken place. This objection is obviated in the present invention by closing the upper end of the nozzle by means of a fragile disk 30. This disk prevents the liquid which freely flows through the large openings 31 in the tube 34 from passing out through the nozzle until sufficient pressure has been generated by the mixing of the two liquids, to cause the disk 30 to break. The resistance power of the disk against breakage can be regulated so that it will only give way when complete chemical reaction has taken place, and a certain predetermined gas pressure produced.

In Figure 2 I have illustrated a modified form of my invention wherein 40 designates an air tight and liquid tight container of any suitable size and shape, and made of cast iron or other suitable material capable of withstanding considerable pressure. The container 40 and the bottle 41 are filled with any known chemicals which when mixed together will form an efficient fire extinguishing gas under pressure. Any suitable means such as brackets 42 may be employed to detachably connect the container 40 to the ceiling or wall of a room or building.

The lower end of the container 40 is formed with a threaded opening 43 in which is screwed a flanged ring 44 having an opening 45 in which seats the conical portion 46 of a valve or closure 47, a cork or other packing ring 48 interposed between the ring 44 and the annular shoulder 49 on the valve forming a liquid tight joint between these parts. The valve 47 is normally held in closed position by a plate or rod 50 hingedly supported at one end as at 51 to a lug 52 carried by the ring 44. The opposite or free end of this plate or rod 50 is connected to the container by means of a readily fusible member or link 53, thereby holding the closure or valve tightly to its seat.

Formed on or suitably attached to the ring 44 is a spider 73 which serves as a guide for the stem 54 of a nozzle 55, normally resiliently held against the inner face of

the valve or closure 56 by a coil spring 57 engaging at its upper and lower ends respectively with the spider 73 and nozzle 55.

The bottle 41, previously described as containing a suitable chemical, is securely held within a seat or holder 56, pivotally supported at 58 to a bracket 59 bolted or otherwise suitably attached to the inner wall of the container 41. The position of the bottle 41 with respect to the hinge 58 is such that while the bottle will be normally maintained in upright position a minimum of effort will be necessary to tip the bottle out of equilibrium.

In the event of a fire occurring in proximity to the container 40 the readily fusible link 53 will give way under action of the heat and the pressure of the nozzle 55, and hinged plate 50 will be caused to swing to open position on its hinge 51. Simultaneously with this movement of the plate 50, the valve 47 is opened as the nozzle 55 is forced outwardly through the opening 60. The outward movement of the nozzle is limited by the flange 61 coming in contact with the flanged ring 44, the former being preferably provided with a packing washer 62 to effect a tight joint between said flange and ring.

Outward movement of the nozzle causes the bottle 41 to be tilted sufficiently to cause its contents to be spilled into the main container in the following manner. The stem 54 of the nozzle is hingedly connected to a lug 63 formed on and projecting from the bottle holder 56 by means of a link 64. Consequently downward movement of the stem 54 causes the bottle holder to rock upon its pivot 58, it being understood that the bottle stopper 65, which is loosely seated within the mouth of the bottle, will become unseated when the bottle is tilted. The bottle stopper is preferably tapered and also weighted at its top portion to insure its dropping out of the bottle, and the spilling of the contents thereof when the bottle is tilted to approximately horizontal position. A chain 66 connected at opposite ends to the bottle stopper and to the cap or closure 66 of the container 40 prevents the bottle stopper from falling into the container. This chain also serves to pull the stopper from the neck of the bottle when the latter has reached the limit of its downward tilting movement, in the event the stopper should not drop out by force of gravity during such movement. It will be understood that the bottle is securely clamped or otherwise fixed to the seat or holder 56 to provide against displacement during tilting.

In order to prevent the liquid from escaping while chemical reaction is taking place as the result of mixing the two ingredients, a fragile disk 67 is placed over

the top of the nozzle 55, the function and operation of this disk being identical with that of the disk 30 of Figure 1.

Having thus described my invention, 5 what I claim is:

1. A fire extinguisher comprising a main container having an outlet opening, means in said container for containing chemical substances which when mixed together 10 generate a fire extinguishing gas, a valve for normally closing said outlet opening, automatic means for bringing said chemical substances into contact with each other when said valve is opened, and means for 15 closing said valve opening after said valve has been opened until a predetermined chemical reaction has taken place in said container.
2. A fire extinguisher comprising a main 20 container having an outlet opening, means in said container for containing chemical substances which when mixed generate a fire extinguishing gas, a valve for normally closing said outlet opening, automatic 25 means for bringing said chemical substance into contact with each other when said valve is opened, and fragile means for temporarily closing said valve opening after said valve has been opened.
3. A fire extinguisher comprising a main 30

container having an outlet opening, means in said container for containing different chemical substances which when mixed generate a fire extinguishing gas, a valve for said outlet opening, fusible means for 35 maintaining said valve in closed position, a nozzle normally extending into said outlet opening and resting upon said valve and adapted to extend through said opening when said fusible means is rendered inoperative 40 and said valve opens, means for mixing said chemical substances upon the opening of said valve, and a fragile disk closing one end of said nozzle.

4. A fire extinguisher comprising a main 45 container having an outlet opening, means in said container for containing chemical substances which when mixed together generate a fire extinguishing gas under pressure, and fragile means for preventing the 50 escape of gas through said outlet opening until the said gas exerts a predetermined pressure against said fragile means.

In testimony whereof I affix my signature in presence of two witnesses.

HAROLD A. BRAMAN.
